UNITED STATES PATENT OFFICE.

CARL S. STORRER, OF WINTERTHUR, SWITZERLAND.

PENCIL-SHARPENER.

1,362,055.

Specification of Letters Patent. Patented Dec. 14, 1920.

Application filed September 1, 1914, Serial No. 859,625. Renewed May 20, 1919. Serial No. 298,556.

To all whom it may concern:

Be it known that I, CARL S. STORRER, a citizen of the Republic of Switzerland, residing at Winterthur, Switzerland, have invented new and useful Improvements in Pencil-Sharpener; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

15 Machines used for sharpening lead pencils, colored pencils and the like, which act upon the wooden shaft and the core of graphite, color and the like, are already known. In the hitherto proposed pencil 20 sharpeners the wooden shaft and the core of the pencil are acted upon in a single cutting plane, so that it is impossible to obtain a sharp, lengthened graphite or color point and the latter cannot be sharpened in any 25 desired manner.

The object of this invention is to provide a machine for sharpening lead pencils, colored pencils and the like, in which the hereinbefore mentioned drawbacks are eliminated. To this end there is imparted according to this invention to at least one knife having a stepped or broken cutting edge such a relative movement with respect to the lead or color pencil, that said edge is 30 brought to act at first during a course of work in a cutting plane upon the wooden shaft and afterward in a plane, which is different from the first mentioned one, upon the core of graphite and color respectively. In other 35 words, a cut is produced on the pencil in a broken line, *i. e.*, a line formed of a number of lines joined at their ends and not forming a continuous straight line, said broken line extending from the periphery of the 40 pencil to or through the axis thereof.

In the accompanying drawings:

Figure 1 is a front elevation partly in section of a first embodiment of the invention,

50 Fig. 2 is a horizontal section on the line 2-2 of Fig. 1,

Fig. 3 is a side view of this sharpener,

Fig. 4 is a vertical section on the line 4-4 of Fig. 1,

55 Figs. 5-7 show front elevations of different shaped cutting knives,

Figs. 8-10 show these knives in their different working positions relatively to the lead pencil and colored pencil respectively,

Fig. 11 is a vertical section of the pencil holder,

Fig. 12 is a horizontal section on the line 12-12 of Fig. 11,

Fig. 13 is a top view of the feeding mechanism for the revolving sleeves of the pencil holder.

The embodiments of my invention illustrated in the accompanying drawings comprise a box-like receptacle 1 provided with a drawer 2 for the shavings. To the top of 70 the receptacle 1 is fixed a two-parted casing 3 supporting a horizontally mounted shaft 4. To this shaft 4 is fixed outside the casing 3 a crank 5 and inside said casing a cam disk 6 having three equally shaped lifting cams 7 formed by providing a correspondingly shaped lateral slot 8 milled out of the cam disk 6. Each lifting cam 7 has a steep lifting curve 7¹ and an adjacent less steep lifting curve 7² as well as a steep 75 downward sloping curve 7³. The curve 7¹ of each of said lifting curves 7 imparts a quick movement to the knife carrier relative to the wooden shaft of the pencil, while the second (7²) of these curves imparts to the 80 knife carrier a slower movement relative to the core of graphite or color of said pencil. The downward sloping curve 7³ causes a quick return movement of the knife carrier (Figs. 1, 2 and 4).

90 A roller 9 mounted on an arm 10 projects into the slot 8. The arm 10 is fixed to a horizontal shaft 11 supported in the front wall of the casing 3. To this shaft 11 is fixed the knife carrier consisting of an arm 95 12. This arm carries on its upper end a deflection 12' lying in the plane of this arm and having a bearing surface for a knife 13; said bearing surface is arranged obliquely with regard to the path of movement of the 100 arm 12 and it has two noses 14 projecting into corresponding recesses 15 provided in the knife and serving for securing the latter in its proper position. The knife is secured to the arm 12 by means of a clamp screw 105 16 screwed into the deflection 12' and a clamp plate 17 resting on the knife and acted upon by the head of said screw 16. (Figs. 1-3).

Upon a rotation of the cam disk 6 in the 110 direction of the arrow shown in Fig. 1 the arm 12 is caused to swing by each of the

three lifting cams of the curved slot 8 from the upper position shown in Fig. 1 in full lines into the position shown in point and dash lines and it is then afterward returned 5 into its normal position. Thereby the downward movement of the knife carrier, which corresponds to the cutting motion of the knife is effected by steps and at different speeds in accordance with the different steep slopes of the lifting curves 7¹ and 10 7² of the lifting cams 7.

On the level of the shaft 4 there is mounted in the casing 3 a pencil holder 18. The latter is carried by an arm 19 attached 15 to the casing by means of a screw 20 and secured against displacement by means of a pin 21 fixed to the holder 18. The holder 18 is adjustably mounted on a bolt 22 screwed into the arm 19, the pin 21 preventing thereby an accidental rotation of 20 this holder 18. A spring 23 surrounding the bolt 22 presses the holder 18 against the arm 19. For the purpose of rotating the holder 18, there is fixed to it a button 24, so 25 that this holder 18 can be moved outward against the action of the spring 23 and shifted in the longitudinal direction of the bolt 22. The pencil holder 18 has two borings 25 and 25' of different size to receive lead and colored pencils of different thicknesses. These 30 two borings are parallel to each other and they form an angle with the plane of movement of the knife. They have the shape shown in Fig. 11, *i. e.* they consist of cylindrical and tapered longitudinal parts. The cylindrical outer part of each boring acts as a bearing for a revolving sleeve 26 or 26' respectively, provided with a feeding wheel 27 or 27' respectively, fixed to this 35 part and having also resilient wire clamps 28 or 28', respectively. The clamps 28 or 28' respectively, are jammed tightly between a flange of the sleeve and the feeding wheel and the free, resilient shanks or legs 40 of them project through slots of the sleeve 26 or 26' respectively, into the boring of the latter (Fig. 12). These resilient clamping shanks hold fast the lead or colored pencil inserted into the sleeve 26 or 26' respectively. To retain the sleeves 26 and 26' in the borings 25 and 25' there are fixed 45 to the holder 18 flat stirrups 29 and 29' respectively, passing over the feeding wheels 27 and 27'. The sleeves 26 and 26' 50 of the holder 18 may be moved by jerks in the borings 25 and 25'. To this end there are provided on the circumference of the cam disk 6 three noses 30 lying opposite the lifting cams 7 and actuating an operating lever 31 (Fig. 13), which carries a spring controlled pawl 32 engaging the ratchet wheel 27. The sleeves 26 and 26' 55 are rotated whenever the knives 13 act upon the pencil, *i. e.* while the knife carrier 12 is moved back into its upper position.

The corresponding ends of the borings 25 and 25' lie in two parallel planes 18' (Fig. 11) of the holder 18. One of these planes (in the embodiment of the invention shown is the plane in which lies the end of 70 the boring 25) corresponds to the plane of movement of the knife, while the other one of said planes lies opposite the first mentioned plane (Fig. 3). These sides or planes 18' touch the outermost mantle-line 75 of the conical longitudinal parts of the borings 25 and 25' (Figs. 3 and 11). The holder 18 has also stops 33 and 33' limiting the feed of the pencil in the borings 25 and 25'. 80

Beneath the knife carrier there is provided in the receptacle 1 an opening 34 and above this opening is fixed a sheet iron plate 35 guiding the shavings whittled away during the course of work of the knife 85 toward the opening 34, so that they may fall into the drawer 2 (Figs. 2 and 4).

Figs. 5-7 illustrate three knives 13, which have two-stepped cutting edges of different shape and which may be used in 90 the hereinbefore described machine. The knife shown in Fig. 5 has a stepped cutting edge 36, 37, while the knives shown in Figs. 6 and 7 have broken edges consisting of a straight part 36 and a part 38 or 39 95 respectively, which is situated in a different plane than the straight part 36. The cutting edge 36 of the three knives shown serves to whittle away the wood in one plane, while the cutting edges 37-39 serve 100 to cut off the core of graphite or color in a different plane. The edges 36 and 37 of the knife illustrated in Fig. 5 are parallel to each other, while the edge 38 of the knife shown in Fig. 6 has a curved and concave shape and the edge 39 of the knife shown in Fig. 7 is inclined with reference to the edge 36. The knife is set at an angle of about 15° to the plane or movement while the cutting edge 36 is beveled at an angle 110 of 15° to the plane in which the knife is set and the edges 37-39 are beveled at an angle of 30° to said plane in which the knife is set. The knives 13 consist of thin steel blades. For the sake of clearness I 115 have shown in the drawings (Figs. 8-10) the knives much thicker than they are actually made.

The hereinbefore described pencil sharpener acts as follows: 120

Let us assume, that a preparatory roughly cut pencil having a stump and a used up graphite point has to be sharpened and that a knife of the type shown in Fig. 5 has to be used. If this is the case the pencil is inserted as shown in the drawings, into the sleeve 26 of the holder 18, the cam disk 6 is then rotated by means of the crank 5 in the direction of the arrow shown in Fig. 1, the lifting cams 7 acting thereby one after 125 130

another upon the knife carrier 12. The latter is thus oscillated to and fro together with the knife. Upon each downward movement of the knife carrier the edge 36 of the knife 5 13, which is moved from the position I shown in Fig. 8 downward, whittles away a shaving from the wooden shaft of the pencil projecting beyond the side 18' of the holder 18. Owing to the fact that the knife cuts 10 thereby the axis of the pencil along a circular line, the cutting edge 36 comes at a certain moment out of contact with the wooden shaft of the pencil (position II, Fig. 8) before the cutting edge 37, which is set 15 back with respect to the edge 36, begins to act upon the core of graphite, so that a part of the latter will not come in touch with said edge. This part of the core maintains therefore its full cross-sectional area. Only after 20 that the cutting edge 37 has been moved into the position III, it will begin to act upon the graphite core and cut off the graphite in the same manner as the edge 36 whittles away the wooden shavings. In the position IV 25 the cutting edge 37 comes then also out of contact with the graphite core and the knife is again moved upward, one of the noses 30 acting thereby upon the feeding device 31, 32, 27, so that it causes a partial rotation of 30 the pencil. It will be seen by referring to Fig. 8 that the line of cut is a broken one as the line from I to IV is not straight. The straight line from I to II and the straight line from III to IV are not continuous, but 35 are joined at their adjacent ends by the line from II to III.

In this manner the pencil is gradually acted upon all around by the two edges 36 and 37 of the knife, which begins to cut out a 40 core as well of the wooden shaft as of the core of graphite. Afterward the knife pushes the pencil to a certain amount downward and the latter is then again acted upon all around by said knife. The sharpening 45 operation proceeds in this manner till the graphite point strikes against the stop 33, in which case the pencil point will then have the desired shape. If an unsharpened pencil has to be sharpened, the cutting edge 36 50 whittles away all around the wooden shaft till the core of graphite is laid bare, whereupon the latter is cut off in the hereinbefore described manner by the cutting edge 37, the wood being whittled away during the same 55 course of work by the cutting edge 36. In accordance with the shape of the lifting cams 7 and the slot 8 respectively, the cutting speed of the knife of the hereinbefore described machine will be greater during the 60 first cutting phase when the edge 36 is beveled at a small angle with respect to the wooden shaft to be cut off, and it will be smaller during the second cutting phase, when the edge 37 is beveled at a greater angle with regard to the harder core of graph-

ite. In this latter case the graphite core will be more scraped off than cut off.

If a knife of the kind shown in Fig. 6 is used the pencil will be sharpened in the manner shown in Fig. 9, *i.e.* the cutting edge 70 36 of the knife 13 cuts off a shaving of the wooden shaft along a straight line upon said edge being moved from the position I into the position II, while the cutting edge 38 moved from the position II into the position 75 III cuts the core of graphite along a curved line deviating from the straight cutting direction of the knife. Here also the cut from I to III is in a broken line. Thus, the sharpening machine begins to cut a core out of the 80 wooden shaft and a point having a convex outer surface out of the core of graphite.

If a knife of the kind shown in Fig. 7 is used, a core will be cut out of the wooden shaft by the edge 36 while the knife is 85 moved from the position I into the position II (Fig. 10) and upon a movement of the knife from the position II into the position III the cutting edge 39 begins to cut a conical shaped point out of the core of 90 graphite, the mantle-line of said point forming then a broken line with the mantle-line of the wood-cone.

Instead of moving the knife with respect to the pencil along an arc shaped line, it 95 may as well be moved along a straight line cutting the axis of the pencil.

The resilient shanks or legs of the wire clamps 28 and 28' of the holder 18 can not only give way radially, but they may also 100 give way outward in a lateral direction to permit the insertion of round pencils and of pencils having eight edges as well as of six cornered pencils into the sleeves 26 and 26', in which they are held fast by said clamps 105 28 and 28'.

In the hereinbefore described machine for sharpening pencils there is obtained a lengthened sharp point of the core of graphite or color forming the continuation of the 110 lengthened wooden cone of the pencil.

What I wish to claim is:

1. In a machine for sharpening lead pencils and the like, a knife having cutting edges in different planes, a pencil holder, 115 and means for moving the knife in a plane longitudinally of the pencil to produce a shearing cut, one of said cutting edges acting at first during each course of work in a cutting plane upon the wooden shaft, the 120 other of said cutting edges subsequently acting on the core in a cutting plane, which differs from the first mentioned one.

2. In a machine for sharpening lead pencils and the like, a knife having cutting edges in different planes, a knife carrier, a pencil holder, and means for moving the knife carrier longitudinally of the pencil to produce a shearing cut at varying speeds 125 with respect to the wooden shaft and the 130

core of the pencil, whereby the projecting part of one of the cutting edges of the knife acts first on the shaft at a great speed in one cutting plane, while the other of said edges 5 acts afterward on the core at a smaller speed in a cutting plane which differs from the first mentioned one.

3. In a machine for sharpening lead pencils and the like, a knife provided with two 10 adjacent cutting edges arranged in the longitudinal direction of the knife and having different bevels, a knife carrier, a pencil holder, and means for moving the knife carrier longitudinally of the pencil to produce 15 a shearing cut, said knife acting first on the shaft with the one of said cutting edges and afterward with the other one of said edges upon the pencil core.

4. In a machine for sharpening lead pencils and the like, a knife, provided with a 20 stepped cutting edge, the two parts of the edge having different bevels, a knife carrier, a pencil holder, and means for moving the knife carrier longitudinally of the pencil to 25 produce a shearing cut at varying speeds with regard to the wooden shaft and the pencil core, the projecting part of the cutting edge having a small bevel acting at a great speed in a cutting plane upon the 30 wooden shaft, while the other part of said cutting edge having a greater bevel acts afterward upon the core at a smaller speed in a cutting plane, which differs from the first mentioned one.

35 5. In a machine for sharpening lead pencils and the like, a knife having two adjacent cutting edges arranged in the longitudinal direction of the knife, a movable knife carrier, clamps for securing the knife to said 40 carrier, a pencil holder and means for moving the knife carrier transversely and longitudinally of the stationary pencil at varying

speed with respect to the wooden shaft and the pencil core along a line cutting the axis of the pencil, one of said cutting edges acting at a great speed upon the wooden shaft, while the other one of said edges acts afterward at a smaller speed upon the pencil core, the two cutting planes being different from one another.

6. In a machine for sharpening lead pencils and the like, a pivotally mounted knife carrier, a knife consisting of a thin blade of steel having a stepped edge, the two stepped portions of which have different 55 cutting edges, means for securing the knife to said carrier, a pencil holder comprising a rotatable sleeve to receive the pencil and wire clamps for holding the pencil, a revolving cam disk having a lateral curved 60 slot, a roller on the knife carrier projecting into said slot, said slot being provided with a plurality of lifting cams, each of which has a steep and a less steep lifting curve for the knife carrier so that the latter is moved 65 transversely and longitudinally of the pencil upon a rotation of said cam disk, the projecting part of the cutting edge having a small bevel acting first on the shaft at a great speed in one cutting plane, the other 70 part of said cutting edge subsequently acting on the core at a smaller speed in a cutting plane which differs from the first mentioned one, and means for revolving the sleeve together with the pencil during the 75 return movement of the knife carrier.

In testimony that I claim the foregoing as my invention, I have signed my name in presence of two subscribing witnesses.

CARL S. STORRER.
